[57] CLAIM

The ornamental design for a boat control panel, as shown and described.

DESCRIPTION

FIG. 1 is a perspective view of the design for a boat control panel, the broken lines indicating the boat bow mounting environment and not forming a part of the design.

FIG. 2 is a front elevational view of the design of FIG. 1 on a larger scale.

FIG. 3 is a cross-sectional view of the design of FIG. 1, taken partially on the line 3—3, FIG. 2.

FIG. 4 is a side elevational view of the design of FIG. 1, the opposite side thereof being identical.

FIG. 5 is a top plan view of the design of FIG. 1, the bottom view thereof being identical.
